UNITED STATES PATENT OFFICE.

CHARLES G. DUFFY, OF NEW YORK, N. Y.

SAMPLE-CASE.

1,077,686.

Specification of Letters Patent. Patented Nov. 4, 1913.

Application filed May 25, 1912. Serial No. 699,797.

To all whom it may concern:

Be it known that I, CHARLES G. DUFFY, a citizen of the United States, residing in the borough of Brooklyn, in the city and 5 State of New York, have invented certain new and useful Improvements in Sample-Cases, of which the following is a specification.

My invention relates to sample cases 10 which are provided with sliding drawers, and it consists in certain improvements whereby the movement of the drawers is made to open and close their coöperating doors, as is hereinafter pointed out and 15 claimed.

In the drawings Figure 1 is a side elevation, partly in section, of a case embodying my improvements; Fig. 2 is a cross sectional view, taken on the line 1—1 of Fig. 1, Fig. 20 3 is a plan view of the sliding track frame, Fig. 4 is a sectional detail showing the connection between the drawer, sliding track frame and case; and Fig. 5 is a detail, on an enlarged scale showing the hinge connection 25 between the case door and its follower and a special door stop.

In all the figures the same reference letters designate the same parts.

The case 2 is divided into compartments, 30 in the usual manner, and is provided with suitable guides or rails 3 to support the drawers 4, 4.

A sliding track frame is formed of two parallel rails 5, 5, which slide on the rails 3, 3, and are held thereupon by the under-gripping ends of the cross bars 6, 6. The movement of the track frame is facilitated by antifriction rollers 7, 7 in the front cross bars of the case. The track-frame rails 5, 5, 35 are, also, provided near their forward ends with antifriction rollers 8, 8, and with spring stops 9, 9, which normally stand out, as shown in Fig. 2, so as to prevent the undercut blocks 10, 10 on the bottom of the 40 drawers 4, 4, from being slid out from the rabbets 11, 11 in the lower sides of the track-frame rails 5, 5. But, when these spring stops 9, 9, are pressed against their respective rails, the blocks 10, 10, may be drawn 45 off the front ends of the track-frame. The forward cross-bar 6 will engage with the front cross-bar of the case to stop the forward movement of the track-frame, and a suitable stop, as 12, engaging with the 50 drawer causes the track frame to be carried back into the case with the drawer. It will

be seen that this arrangement provides an extended support for the drawer, to which it is normally secured, and in coöperation with which it may be slid in and out with 60 very little friction.

The sides of the drawers are inclined, at their front ends, preferably on a curve, as shown at 13; the front end of the drawer bottom is provided with a backward slope 65 14; and the upper edges of the sides carry cogged tracks 15, 15, into which mesh toothed gears 16, 16 are attached to the inner sides of the case. These gear wheels 16, 16 are preferably provided with ball-bearings, 70 and they may conveniently be mounted between bars 17, 17, between which are also mounted antifriction rollers 18, 18, which may be grooved, as shown, so as to straddle the tracks 15, 15, and 19, 19, and bear 75 against the smooth margins of the latter, outside of the cogs. But stationary bearings or a smooth track may be provided instead of the roller bearings, 18, 18, if desired. The doors 20, 20, are provided with 80 sloping lower edges, 21, 21, to coöperate with the inclined drawer ends 14, 14; and to their backs are secured the tracks 19, 19, which mesh with the gear wheels 16, 16. These doors are hinged to followers 22, 22, 85 which serve to guide and steady the movements of the doors, so as to prevent jarring and binding, and also to carry the part of the tracks 19, 19 which remains in engagement with the gear wheels 16, 16, when the 90 doors are closed. It will be seen that this guiding movement will be conveniently accomplished by plain extensions of the tracks 19, 19 running in the grooves of the wheel 18, 18. But any other suitable system of 95 guides may be used.

Spring stops 24, 24, similar to the spring stops 9, 9, are attached to the sides of the case, and are adapted to engage in recesses 25, 25 in the edges of the follower, so as to stop its forward movement. Holes 26, 26 open through the sides of the follower behind the spring stops 24, 24; and by inserting pins or rods through these holes the 100 springs may be depressed so that the follower may be drawn forward out of the case.

The operation of my device is as follows: When the drawer is slid back and the door closed, as shown in the second compartment from the top in Fig. 1, if it is desired to 110 open the case, the drawer is grasped by the handle 23 and drawn forward, sliding over

the track frame rails 5, 5. And as the drawer moves, the forward edges 13 press against the back of the door 20, causing it to swing out and upward, until it approximates a horizontal position, when the forward end of the cogged track 15 will engage with the gear wheel 16, causing the latter to revolve, and carrying back the track 19 and with it the follower 22 and the door 20.

10 And this movement may be continued until the parts reach the position shown in the upper portion of Fig. 1, when the gear wheels 16, 16 will be at the end of the tracks 15, 15; and, if it is desired to do so, the spring stops 9, 9 may be pressed in, and the drawer entirely detached from the case. The case is closed by pushing in the drawer; which causes the cogged wheels 16, 16, to draw forward the door and follower, until

20 the tracks 15, 15 have passed under the cogged wheels, when the follower will be in substantially the position shown in the second compartment from the top of Fig. 1, and the door will be resting upon the forward edges of the drawer. The door will then swing in, as the drawer is pushed back, and it will finally close into the position shown in the second compartment, in Fig. 1, the inclined edges, of the door and of the drawer coöperating to make a locking joint.

25 In Fig. 5 I have shown the gear wheel 16 as set farther back from the front of the case than in the other figures; and a door stop 27

as placed in front of it, so that when the door is closed the stop 27 will prevent the 35 door and its follower from being accidentally pushed back into the case. When the gear wheels 16, 16 are set forward as shown in Fig. 1 they act as door stops. But under some circumstances it may be preferable to 40 use separate stops, as 27.

Having thus described my invention, what I claim and desire to secure by Letters Patent of the United States is:—

The combination, with a sample-case 45 frame, of a drawer provided with a projecting, transversely-grooved bottom and sides backwardly curved at their forward ends and with cogged racks along their upper edges, a cogged wheel adapted to mesh above 50 each of said racks, a sliding door-guide provided at each side with a section of cogged rack adapted to engage above one of said cogged wheels, a downwardly swinging door hinged to the forward end of said door-guide and provided with a backwardly and downwardly beveled lower edge to engage in 55 said transverse bottom groove, and also provided at each side with a section of cogged rack adapted to engage above one of said 60 cogged wheels.

CHARLES G. DUFFY.
